United States Patent Office

Des. 208,502
Patented Sept. 5, 1967

208,502

PAIR OF INVERTIBLE SUNGLASSES

David Halpern and George Weisenfeld, both of 1432
S. Los Angeles St., Los Angeles, Calif. 90015

Filed Sept. 19, 1966, Ser. No. 3,923

Term of patent 14 years

(Cl. D57—1)

FIG. 1.

FIG. 2.

FIG. 3.

FIGURE 1 is a perspective view of a pair of invertible sunglasses, showing our new design;

FIGURE 2 is a top plan view; and

FIGURE 3 is an elevational view thereof taken from the right side of FIG. 1, in inverted position.

We claim:

The ornamental design for a pair of invertible sunglasses, as shown.
